US00D728562S

(12) **United States Design Patent**
Park et al.

(10) **Patent No.:** US D728,562 S
(45) **Date of Patent:** ** May 5, 2015

(54) **MOBILE PHONE**

(71) Applicant: **LG Electronics Inc.**, Seoul (KR)

(72) Inventors: **Sangmin Park**, Seoul (KR); **Seunghoon Ryu**, Goyang-si (KR); **Jonghak Lee**, Cheonan-si (KR); **Eulseok Lee**, Seoul (KR)

(73) Assignee: **LG Electronics Inc.**, Seoul (KR)

(**) Term: **14 Years**

(21) Appl. No.: **29/481,087**

(22) Filed: **Jan. 31, 2014**

(30) **Foreign Application Priority Data**

Aug. 2, 2013 (KR) 30-2013-0040139

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof where the bottom plan view is a mirror image.

The broken lines in FIG. 3 depict parts of the mobile phone that form no part of the claimed design.

1 Claim, 6 Drawing Sheets
